UNITED STATES PATENT OFFICE.

HENRY W. HUBERS, OF DAVENPORT, IOWA.

TIMING DEVICE FOR WASHING MACHINES.

Refiling of application Serial No. 475,468, filed June 6, 1921. This application filed December 17, 1926.
Serial No. 155,533.

My invention relates to timing devices for washing machines, and is more specially designed for use in connection with that class of such machines which are electrically operated or controlled, this application being a refiling of my former application No. 475,468 filed June 6, 1921. One of the purposes thereof is to provide for the automatic interruption of the power devices of the machine at the end of a predetermined period of time, with associated means for varying such period of time at will.

Another purpose of the invention is to provide means whereby the operation of the machine can be manually stopped for a time, and started again, without interfering with the period of time for which the machine was originally set, the original period of time being held in abeyance while the machine is idle. By this means it will be possible for the operator to make changes in the contents of the machine before the period has fully run, and then have the operation continue for the unexpired time.

Another feature of the machine consists in a suitable closure for the mechanism thereof, which is associated with the power interrupting devices in such a way that whenever such closure is opened the operation of the machine will cease. This will render it impossible for young children to become injured by such mechanism.

The particular construction, arrangement, and operation of the various parts of the machine will be more fully understood from the following specification, reference being had to the drawings accompanying the same, in which;

Fig. 1 is a side elevation of a washing machine, with a portion of the casing broken away to disclose my invention embodied therein.

Fig. 2 shows said invention in plan view, in position when in use.

Fig. 3 is a detail of the door fastening devices, from the inside of the door.

Fig. 4 is a similar view, from one side thereof.

Fig. 5 is a plan view of said fastening devices, with a portion of the frame in section.

The main power mechanism of the machine is not involved in the present invention, except in so far as it is controlled by the action of the timing devices, so that such

mechanism will not be particularly set forth herein. As will be obvious, the timing devices are capable of adaptation to any washing machine possessing movable parts which have a recurrent action.

1 represents the frame of a washing machine of a common pattern and 2 the tub mounted therein. Pivoted to a cross-bar 3 as at *a*, is a rack 4, the teeth of which are in mesh with the teeth of a gear-wheel 5, (indicated in broken lines) fixed on a shaft 6, in rear of a shield 7, supported in front of the bar 3. Within the tub the shaft 6 is fitted with the usual washing mechanism.

Mounted on cross-pieces 8 in the lower part of the frame is a main drive-shaft 9, to which power may be imparted in any known manner, but preferably from an electric motor, as shown at A, through a belt and wheel 10 on the shaft 9. The wheel 10 is connected with the rack 4 by means of a pitman 11, whereby a reciprocating movement may be imparted to such rack, giving to the wheel 5 and shaft 6 the desired movement.

The front part of the frame is provided with a door 12, shown partly broken away in Fig. 1, the upper edge of said door, when closed being in contact with a cross-piece 13, and above said door is a plate 14, closing the space above said door. Said door and plate are spaced apart from the tub 2, and to the face of said tub is fixed a vertical shaft 17. Upon the shaft 17 is rotatable a wheel 18, provided on its inner edge with an annular series of ratchet teeth 19, engaged by the end of an arm 20, pivoted to the upper end of a lever 21, fulcrumed on the plate 15, as at *b*. In the upward movement of the rack 4 the lower end of the lever 21 is engaged thereby, swinging the same to one side, and causing a movement of the wheel 18 equalling the length of one of the teeth thereon. As the rack moves downwardly again the lever 21 returns to its former position, the lever being prevented from swinging past a central point by means of a lug 22 thereon, which comes in contact with a stop 23 on the plate 15.

Secured to the plate 15 is a bearing 25, in which is loosely supported a shaft 26, on which is fixed a toothed wheel 27, the teeth of which are adapted for engagement with a spiral rib 29 on the periphery of the wheel 18. One complete revolution of the wheel

18 will thereby be caused to give to the wheel 27 a partial rotation to the extent of one of the teeth thereof.

Supported from the plate 15 is a switch-box 30, provided with a switch-pin 31, such switch being in electrical circuit with the power actuating devices of the machine, so that when the circuit is broken in such switch-box the machine will not be in operation. Fulcrumed on a support 32 fixed to the plate 15 is a lever 33, one end of which is in contact with the end of the switch-pin 31, and the other end of which is adapted for engagement by a pin 34 projecting inwardly from the face of the wheel 27. When the wheel is suitably rotated the pin comes in contact with the lower side of the lever 33, rocking the same on its fulcrum and causing the opposite end thereof to force the pin 31 downwardly, actuating the switch 30^a in the box 30. Such switch is normally in closed position, so that the circuit will be complete in the electrical system of the machine, and the action of the pin 31 operates to open the circuit, and interrupt the movement of the machine. When the pressure of the lever 33 is removed from the pin the circuit is again closed. The inner end of said lever is slightly longer than the other end, so that the tendency of such inner end will be to move downwardly, relieving the pressure on the pin.

The outer end of the shaft 26 is slidable in an opening in the plate 14, and is provided at its outer end with a knob 28, by means of which it can be rotated. Said wheel can thereby be set with the pin 34 at such a position with relation to the lever 33 that in the ordinary operation of the machine a considerable period of time would elapse before the pin would engage the lever. For example, the wheel could be set with the pin immediately above the lever, as shown in Fig. 2, in which case the wheel would have to describe almost a complete revolution before the lever would be actuated. In order that the wheel 27 may be rotated freely the shaft 26 is pulled outwardly, releasing the teeth of the wheel from engagement with the rib 29.

It will be obvious that the wheel 18 will receive successive impulses from the recurrent action of the rack 4, giving a slow rotary movement to such wheel, and that this movement will be imparted to the wheel 27, rotating the same at a greatly reduced rate of speed. By this means the tub mechanism can be permitted to operate for a usual length of time, and then be automatically interrupted by the action of the switch. For example, assuming that the wheel 18 receives a complete rotation each minute while the machine is operating, and that the wheel 27 contains twenty teeth, such wheel can be set so that the machine will be in

operation for approximately said period of twenty minutes, or for any fractional part thereof. The lower end of the lever 21 is of sufficient weight to cause the same to swing back to a normal position from gravity, after the same has been disengaged by the rack 4.

Supported from the plate 15 is a bearing 35, on which is rotatably mounted a disk 36, provided with a pin 37 which is normally in position just above the outer end of the lever 33. Connected with said disk is a pin 38, projecting outwardly through the casing of the machine, and provided with a push-button 39. By forcing said pin 38 inwardly the disk 36 is rotated sufficiently to cause the pin 37 to move the lever downwardly, throwing the switch. By this means the movement of the machine may be interrupted at any time, for the purpose of attending to the same, or to the contents thereof. By again pulling out the pin the operation of the machine will continue, and operate for the balance of the designated period. It will be evident that several stops of this kind could be made, if desired, and that the sum total of the operations would amount to an operation for the desired length of time.

The free edge of the door 12 is fitted with a catch 40, adapted to be engaged by the long end of a latch 41, which is pivotally mounted in the frame, and the pivot of which is provided with a knob 42, by means of which it can be turned. Pivotally connected with the short end of the latch 41 is a coupling 43, connected with which is one end of a rod 44, the other end of which has a pivotal connection with the disk 36. When the knob 42 is turned for the purpose of opening the door the short end of the latch moves downwardly, actuating the rod 44, and giving a movement to the disk 36, sufficient to operate the switch 30. The movement of the machine is thus interrupted, and there is no possibility of injury to any one from the operating devices which are concealed by the door when it is closed. The movement of the disk 36 draws the push-pin 38 inwardly, and after the door 12 has been again closed the machine is started by pulling such pin outwardly again. The latch 41 and rod 44 are permitted a limited amount of movement independently of each other by means of a straight portion 45 of the rod which works freely in an opening in the coupling 43. The latch can thus be returned from a vertical to a horizontal position without moving the rod upwardly, and it is also possible to actuate the disk 36 by means of the pin 38 without disturbing the latch.

When the latch 41 is in a vertical position the pivotal point of the coupling 43 will be immediately beneath the pivot of the

latch, locking the disk 36 from rotation. In this position it is impossible to start the machine by means of the pin 38, and there is no danger of the machine being inadvertently started by pulling out said pin while the door is still open. On the other hand, if the latch 41 should be turned by a child when the door is open the machinery will not be set in action, but the additional action of the pin 38 is required.

The disk 36 is provided on that side opposite to the pivotal point of the rod 44 with a counter-balance 46, which offsets the weight of the rod, and prevents the same from accidentally turning the disk and throwing the switch.

The preferred embodiment of the invention has been herein disclosed, and changes can be made in the construction, arrangement, and adaptation thereof without departing from the spirit of the invention.

What I claim, and desire to secure by Letters Patent, is;

1. In a washing machine, in combination with the frame of the machine and operating mechanism thereof, a toothed wheel rotatably mounted in said machine and provided with a switch actuating member, a cylindrical wheel rotatably supported in said machine having an annular series of ratchet teeth on one of its ends and provided on its periphery with a spiral rib in engagement with the teeth of said first-named wheel, and a swinging lever provided at one of its ends with a pawl in engagement with said ratchet teeth, and capable of receiving intermittent movements at its opposite end from the recurrent action of said operating mechanism.

2. In a device of the class described, in combination with the frame of the machine and operating mechanism thereof, a toothed member movable therein and provided with a switch actuating member, a rotatable member provided with a spiral rib in engagement with the teeth of said toothed member and having a series of ratchet teeth at one of its ends, a lever adapted for intermittent action by said operating mechanism, and a pawl connected with said lever and in engagement with said ratchet teeth, said toothed member being capable of movement with relation to said rotatable member to free the same from the spiral rib thereon, and permit free movement of said toothed member.

3. In a device of the class described, in combination with the frame of the machine and operating mechanism thereof, an electrical circuit breaking device mounted therein, a lever fulcrumed in said machine and adapted to actuate said circuit breaking device, a toothed wheel rotatably mounted and provided with means for operating said lever, a cylindrical wheel ro-

tatably mounted in said machine, with its axis at right angles with the axis of said toothed wheel, a lever fulcrumed in said machine and adapted to be intermittently actuated by the recurrent movements of said operating mechanism, and means for imparting the movement of said lever to said cylindrical wheel to give partial rotary movements thereto.

4. In a device of the class described, in combination with the frame of the machine and operating mechanism thereof, a switch-throwing member movably mounted in said machine, a toothed wheel rotatably mounted in said machine and provided with means for actuating said switch-throwing member, a cylindrical wheel rotatably mounted in said machine, provided on its periphery with a spiral rib in engagement with the teeth of said toothed wheel, said last-named wheel being capable of movement with relation to said cylindrical wheel to free the same from said spiral rib, a lever fulcrumed in said machine so as to receive intermittent movement from said operating mechanism, means for imparting the movement of said lever to said cylindrical wheel to impart successive partial rotations thereto, a movable member adapted to actuate said switch-throwing member independently of said toothed wheel mechanism, and means for operating said movable member from the outside of the machine.

5. In a device of the class described, in combination with the frame of the machine and operating mechanism thereof, an electrical switch provided with a switch-actuating pin, a lever fulcrumed in said machine having one of its ends in engagement with said pin, a toothed wheel rotatably mounted in said machine, and provided with a member adapted for engagement with the opposite end of said lever, a cylindrical wheel rotatably mounted, having an annular series of ratchet teeth and provided with a spiral rib in engagement with the teeth of said toothed wheel, said toothed wheel being capable of movement with relation to said cylindrical wheel to free the same from the rib thereon, a swinging member adapted to receive intermittent movements from said operating mechanism, and provided with a pawl in engagement with said ratchet teeth, a disk rotatably mounted in said machine, and provided with means for actuating said switch-operating lever independently of said toothed wheel mechanism, and a push-rod connected with said disk and projected without the machine.

6. In a device of the class described, in combination with the frame of the machine and operating mechanism thereof, an electrical switch provided with a switch-actuating pin, a switch actuating lever fulcrumed in said machine, a toothed wheel rotatably

mounted in said machine and provided with means for actuating said lever; a wheel rotatably mounted in said machine and provided with a spiral rib normally in engagement with the teeth of said wheel, said toothed wheel being capable of movement with relation to said second-named wheel so as to free the same from said rib, a member swingingly mounted in said machine so as to receive intermittent movement from said operating mechanism, means for imparting the movement of said last-named member to said ribbed wheel to give successive partial rotations thereto, a hinged closure for said machine, a latch on said frame, adapted to hold said closure in a closed position, and means for imparting the movement of said latch to said switch-actuating lever to operate the same upon said latch being turned to open the door.

7. In a device of the class described, in combination with the frame of the machine and operating mechanism thereof, a switch operating device, a lever fulcrumed in said machine and operatively associated with said switch-operating device, a toothed wheel ro-

tatably mounted in said machine and provided with means for actuating said lever, a cylindrical wheel rotatably supported and provided with a spiral rib normally in engagement with the teeth of said wheel, said toothed wheel being movable with relation to said cylindrical wheel to free the same from said rib, a movable member adapted to receive intermittent movements from said operating mechanism, and operatively connected with said cylindrical wheel to impart successive partial rotations thereto, a disk rotatably mounted in said machine, and provided with means for actuating said switch-throwing devices independently of said toothed wheel mechanism, means for actuating said disk from without the machine, a closure for said machine, a latch pivoted in said frame and adapted to hold said closure in closed position, and means for imparting the movement of said latch to said disk to operate said switch throwing device upon said latch being moved to release said closure.

In testimony whereof I affix my signature.
HENRY W. HUBERS.
